UNITED STATES PATENT OFFICE.

SAUL SCHULHOFF, OF PHILADELPHIA, PENNSYLVANIA.

DESIGN FOR A BOTTLE-CAP STOPPLE.

45,242.

Specification for Design.

Patented Feb. 10, 1914.

Application filed November 5, 1913. Serial No. 799,406. Term of patent 14 years.

To all whom it may concern:

Be it known that I, SAUL SCHULHOFF, a citizen of the United States, residing at the city of Philadelphia, in the county of Philadelphia and State of Pennsylvania, have invented a new, original, and ornamental Design for a Bottle-Cap Stopple, of which the following is a specification, reference being had to the accompanying drawings, forming part hereof, in which—

Figure 1, is a perspective view of the flat circular cap and the integral truncated cone-shaped stopple, showing in entirety my new design; and Fig. 2, is a side elevation of the

cap, showing the particular truncated cone-shape form of the stopple thereof, in integral relationship with said cap.

I claim:—

The ornamental design for a bottle cap stopple substantially as shown and described.

In witness whereof, I have hereunto set my signature in the presence of the two subscribing witnesses.

SAUL SCHULHOFF.
